UNITED STATES PATENT OFFICE

154,613

DESIGN FOR AN OPEN HORSESHOE BOOK END OR SIMILAR ARTICLE

Arthur S. Leitner, Los Angeles, Calif.

Application December 1, 1947, Serial No. 142,895

Term of patent 3½ years

(Cl. D33—1)

To all whom it may concern:

Be it known that I, Arthur S. Leitner, a citizen of the United States, residing in Los Angeles, in the county of Los Angeles, State of California, have invented a new, original, and ornamental Design for an Open Horseshoe Book End or Similar Article, of which the following is a specification, reference being had to the accompanying drawing, forming a part thereof.

Figure 1 is a front perspective view of an open horseshoe book end, showing my new design.

Figure 2 is a front elevational view.

Figure 3 is a side elevational view.

Figure 4 is a rear elevational view.

I claim:

The ornamental design for an open horseshoe book end or similar article, substantially as shown.

ARTHUR S. LEITNER.
